UNITED STATES PATENT OFFICE.

LOUIS T. PYOTT, OF PHILADELPHIA, PENNSYLVANIA.

MEANS FOR SUPPORTING ELECTRIC MOTORS.

SPECIFICATION forming part of Letters Patent No. 611,273, dated September 27, 1898.

Application filed May 14, 1897. Renewed February 23, 1898. Serial No. 671,331. (No model.)

To all whom it may concern:

Be it known that I, LOUIS T. PYOTT, a citizen of the United States, residing at Philadelphia, in the county of Philadelphia and State of Pennsylvania, have invented certain new and useful Improvements in Means for Supporting Electric Motors; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to the supporting of motors upon the trucks of railway-cars propelled by electricity; and the objects of my improvements are to provide an elastic suspension to carry the motor without jars and shocks, to perform the work in a simple and easy manner with few parts, and so applied that the motor can readily be attached to or removed from the truck by the simple unscrewing of a few nuts.

I attain the objects of my invention by the mechanism illustrated in the accompanying drawings, in which—

Figure 1 is an elevation view showing the motor-casing, its suspension, and the cross-pieces, to which the suspension-hangers are attached, and the truck-frame in cross-section. Fig. 2 is a plan showing the same parts. Fig. 3 is an enlarged side view of the suspension-hanger. Fig. 4 is a plan of Fig. 3, while Fig. 5 is a front view of the same. Fig. 6 is a side elevation of one of the motor suspensions, showing it attached to the motor-case; and Fig. 7 is a plan of Fig. 6.

In each view like figures of reference indicate like parts.

Motors have heretofore been suspended upon side lugs removed from the axle-support, but not in manner as here shown. In Fig. 1 one end of the casing 1 has bearings 2 formed to embrace the axle 3, whereon are located the wheels 4, upon which the truck is carried on the rails, and lugs 5, being cast upon each side of the motor-casing, preferably under or over the armature-shaft 6, according to the size of motor, and reaching outward, have heretofore been inserted in levers which by numerous fulcrums, links, le-

vers, and other appliances were finally supported by the truck-frame, generally upon coiled or rubber springs. The numerous parts employed in such instances made it a matter of much work and difficulty to put up or take down the parts when a motor required to be attached to or removed from the truck, and the springs which with such construction were necessarily employed are not of a form to have the flexibility desirable for easy carrying of the motor and its casing to insure freedom from shocks and jars which it is desirable to avoid, not only for the durability of the suspension members, but of the truck itself and the car it carries, together with the comfort to passengers which the absence of such annoyances guarantees. In order to thoroughly overcome all jars and thumping and to enable quick manipulation and at minimum first cost, I place a box 7 over each lug 5, the box 7 having upper and lower flanges 8 projecting beyond the body of the box. The box is of rectangular shape and is embraced at its top and bottom sides by a loop 9 formed on one end of the suspension member 10, the loop being long enough to allow a movement over the box 7 without touching its ends. The suspension member 10 is a single-ended spring having a band 11 near the opposite end from the loop 9, which embraces and secures the plates 12, of which it is composed, and all of which work in unison when yielding and all of which assist in supporting the plate forming the loop 9 and on which the box 7 rests. Plates 12 extend somewhat beyond band 11 for the purpose herein-after described.

Suspension member 10 is secured in a pocket 13, formed in the lower part of bracket 14, secured to and supported by cross-tie 15, which also in this instance rests upon and is secured to the framework 16 of the truck. The pocket 13, in which the suspension member 10 is secured, is open at the side 17 and is recessed at its top, bottom, and back to admit the band 11, and is then contracted, as at 18, to touch plates 12, thus preventing end movement of the suspension member 10, it being held sidewise in the pocket 13 by the hooked bolt 19, which is placed in a groove 20 in bracket 14 and going down underneath the bracket is bent to pass under it in groove

21 and then is turned upward for a distance upon the inner side of the bracket 14. By an examination of Fig. 2 it will be seen bolt 19 passes down by member 10 and band 11 in the angle formed by the end of band 11 and outer side of suspension member 10, thus preventing any movement when the bolt 19 is in its place. Bolt 22 is similarly located at the opposite end of band 11, passing through lugs 10 23 and against the sides of the plates 12, which project beyond the band 11 at 24. The bracket 14 is shown attached to cross-tie 15 by bolt 25, assisted by lug 26 and shoulder 27. It will readily be seen that by lengthening 15 the bracket 14 upon cross-tie 15 more bolts might be applied. The bracket is also shown reaching back and engaging truck-frame member 16, lugged upon its top at 27' and secured by bolt 28. This construction 20 is such as I have applied to the companion sectional truck patented to me January 12, 1897, No. 593,742; but in other forms of trucks not having such a construction as here shown whereon to attach the bracket 14 I can 25 just as readily apply my form of suspension, as a bracket suitably constructed to attach to any cross-tie adapted to reach across and suitably formed to be secured to any of the various forms of truck-frames is all that is es- 30 sential to apply my form of motor suspension.

By reference to Figs. 1 and 2 it will be seen that pockets 13 open outward in brackets 14 of the opposite sides in opposite ways, the open side 17 being toward the outside of the 35 truck, so that all that is necessary to remove the motor suspension is to unscrew the nuts of bolts 19 22 and remove the bolts, when the suspension members 10 can be removed from their pockets 13 and off of lugs 5 with much 40 less work than with any other form of sus- 45 pension heretofore known or used, and I have cheapened the cost of construction by eliminating various small parts working upon each other on delicate bearings liable to rapid wear 50 from being exposed to flying dirt constantly stirred up under the car-body as it moves along over the roadway. I have illustrated a motor-casing with side lugs below the armature-shaft and the axle; but in some forms 55 of motor-casings the suspension-lugs are at a point above the armature-shaft and the axle, and if the same form of truck as I have illus- 60 trated was then used I would rest the bracket upon and above the cross-tie, and it would as 65 readily support the flexible motor-casing as in the arrangement shown, it being merely an adaptation of my invention to suit the varying construction.

Having described my invention, I claim—

- 60 1. In a motor suspension, wheels, axles, a truck-frame and a motor-casing therefor, a cross-tie supported upon and secured to the framework, hangers attached to the cross-tie and secured thereto, flexible supports reach- 65 ing outward and engaging lugs upon the motor-frame, substantially as described.

2. In a motor suspension, wheels, axles, a

truck-frame and a motor-casing, a cross-tie upon the frame, hangers upon the cross-tie, means to secure flexible motor suspensions 70 to the hangers and to lugs upon the motor-casing, substantially as described.

3. In a motor suspension, truck - wheels, axles, a truck - frame, a cross - tie upon the frame, brackets upon the cross-tie, flexible 75 motor-supports secured at one end to the brackets for outward removal, and at their other end looped over and embracing a box around the motor-casing lugs, substantially as described.

4. In a truck-frame supported upon wheels and axles, and carrying a motor and its casing, the motor-casing being attached at one end to the axle and at a point near the armature - shaft, upon either side, having outwardly-projecting lugs, a box embracing each 85 lug, a spring - plate embracing each box at the upper and lower sides of a loop formed thereon, reinforcing spring-plates supporting the plates forming the loop, a band near the 90 opposite end of the plates, brackets having open-sided pockets wherein to place the bands and the spring ends, and means to secure the plates and the band removably to the bracket and the bracket to a cross-tie supported upon 95 the framework of the truck, substantially as described.

5. In a motor suspension, truck - wheels, axles, a truck - frame, a motor - casing sus- 100 pended at one end upon the axle, lugs upon the casing removed from the axle-supports, and yielding and flexible suspension mem- 105 bers one end of which is removably attached to the lugs and the other end removably se- 110 cured to hangers attached to a cross-tie sup- 115 ported upon the framework of the truck, sub- 120 stantially as described.

6. In an electric truck, a truck - frame, wheels and axles, a motor-casing one end be- 110 ing supported upon an axle, lugs upon the 115 casing and thereto removably attached re- 120 sistant supports removably secured at their 125 opposite ends to brackets and a cross-tie car- 130 ried by the truck - framework, substantially as described.

7. In a motor-truck, a framework, motor supported at one end upon an axle and hav- 110 ing a cross-tie upon the framework, means to 115 removably secure thereto one end of longi- 120 tudinal flexible supports, passing by the mo- 125 tor-case and removably engaging lugs thereon 130 at their opposite ends and below the armature-shaft, substantially as described.

8. An electric motor supported by and 115 geared to an axle at one end, near the oppo- 120 site end of its casing provided with flexible 125 and resilient longitudinal side supports en- 130 gaging lugs upon the casing and at their op- 135 posite end removably secured to hangers at- 140 tached to a cross-tie resting on and secured 145 to the framework, substantially as described.

9. In a motor - truck, in combination, a truck-frame, a cross-bar, hangers depending therefrom and removably holding longitudi-

nal flexible and resilient supports extending beyond the cross-bar, and their outer end adapted to be removably secured to the motor-casing, substantially as described.

5 10. In a motor-support, the combination of flexible and resilient supports adapted to be removably connected at one end to the motor-casing and at the opposite end removably secured to pendent means from the truck cross-tie, substantially as described.

10 11. In a motor-truck having a frame and a cross-tie included therein, the combination with one of the truck-axles, of a motor geared thereto, resilient and flexible motor-supports 15 removably suspended from the cross-tie in longitudinal position, reaching thereafter to a point near the armature-shaft and removably attached to and engaging lugs upon the motor-casing, substantially as described.

12. The combination in a motor-truck of 20 wheels, and axles and a framing carried thereby, having a cross-tie secured to the framing within the wheel-base, a motor within a casing adapted to rest upon an axle at one end and flexible and resilient supports for the 25 motor and its casing positively held at one end to the cross-bar and at their opposite end supporting the motor-casing and having means for their disengagement from the cross-tie and the motor-casing, substantially as de- 30 scribed.

In testimony whereof I affix my signature in presence of two witnesses.

LOUIS T. PYOTT.
